UNITED STATES PATENT OFFICE

JAMES MCLEAN, OF GLASGOW, SCOTLAND

GALLERY FOR ELECTRIC LAMPS

Application filed March 22, 1929, Serial No. 349,047, and in Great Britain October 31, 1928.

This invention relates to galleries for electric lamps of the type including a shell having a central aperture for accommodation of the lamp socket and spring-urged arms 5 for engagement with the ornamental bowl, shade or the like carried by the gallery (hereinafter referred to for convenience of description as a bowl).

In practice, it is found that galleries of this type are open to the disadvantage that they are unsuitable for use in relatively small sizes due to the difficulty of inserting the usual screw-threaded ring which is engageable with the screw-threaded neck of 15 the lamp socket and which is usually employed to support the gallery.

In the drawing Fig. 1 is a plan view of the gallery and Fig. 2 a section on the line 2—2 of Fig. 1.

20 The gallery shown comprises a shell 1 having a central aperture 13 for accommodation of a lamp socket 3 and provided with bowl-supporting arms 4 engageable with the interior of a bowl 5. Each arm 4 is secured 25 to an expansile ring 7 floatingly mounted in the shell, being supported by radially disposed pins 8, 9 and 10 loosely fitting in perforations 11 in the circumferential wall of the shell. The pins 8 and 9 may be pressed 30 by the finger and the thumb to compress the ring 7 so as to permit entry of the arms into the bowl 5, the pin 10 serving solely as a support for the ring and sliding in the relative perforation 11. On release of the pins 35 8 and 9 the arms 4 are urged into engagement with the bowl 5 by the expansile ring 7. The shell is formed with tongues 6 which are directed downwardly and inwardly so as to engage the screw-threads 12 of the lamp 40 socket 3. When the lamp socket is pressed into the gallery, the tongues 6 are caused lightly to engage the threads and then forcibly to engage the threads as the weight of the bowl 5 is applied to the gallery.

45 I claim:—

1. A gallery for electric lamps comprising in combination, a shell having a central aperture intended for accommodation of an externally screw-threaded lamp socket and 50 formed around its periphery with tongues

which are directed inwardly so as to engage the screw-threads of said lamp socket, so that, when the lamp socket is pressed into the gallery, the tongues are caused lightly to engage said screw threads and then forcibly to engage the threads as the weight of an ornamental bowl is applied to said shell, and an expansile open ring floatingly mounted on said shell and provided with arms engageable with the interior of such ornamental bowl.

2. A gallery for electric lamps comprising, in combination, a shell having perforations in its lateral wall and formed with a central aperture for accommodation of an externally 65 screw-threaded lamp socket and formed around its periphery with tongues which are directed downwardly and inwardly so as to engage the screw-threads of such lamp socket, so that, when the lamp socket is pressed 70 into the gallery, the tongues are caused lightly to engage said screw-threads and then forcibly to engage said screw-threads as the weight of an ornamental bowl is applied to said shell, and an expansile open 75 ring provided with radial fins loosely accommodated in said perforations and with arms engageable with the interior of such bowl.

In testimony whereof I have signed my 80 name to this specification.

JAMES MCLEAN.
